(74) Attorney, Agent, or Firm — Ruben Alcoba, Esq.

(57) **CLAIM**

The ornamental design for a lace holder, as shown and described.

DESCRIPTION

FIG. 1 is a front side view of a lace holder, showing my new design;

FIG. 2 is a rear side view of the lace holder;

FIG. 3 is a left side view of the lace holder;

FIG. 4 is a right side view of the lace holder;

FIG. 5 is a bottom side view of the lace holder; and,

FIG. 6 is a top side view of the lace holder.

The broken lines in the figures depict environmental structure, and portions of the article which form no part of the claimed design.
